Patented Jan. 5, 1960

187,008

FRAME FOR AN AIRCRAFT WINDOW BAY

Paul J. Petlewski, Detroit, Mich., Marlan H. Polhemus, Chicago, Ill., and Gordon W. Severson, Detroit, Mich., assignors to General Dynamics Corporation, San Diego, Calif., a corporation of Delaware

Application December 31, 1958, Serial No. 54,008

Term of patent 14 years

(Cl. D71—1)

Figure 1 is a front elevational view of a frame for an aircraft window bay showing our new design;

Figure 2 is a side elevational view thereof taken from the left of Figure 1;

Figure 3 is a bottom plan view of the frame;

Figure 4 is a rear elevational view thereof; and

Figure 5 is a vertical cross section taken on the line 5—5 of Figure 4.

We claim:

The ornamental design for a frame for an aircraft window bay, substantially as shown.
